1

The invention described herein may be manufactured and used by or for the Government for governmental purposes, without the payment to me of any royalty thereon.

My invention relates to a novel method of measuring low gas pressures, particularly pressures as low as 10^{-10} millimeter of mercury.

It has been found that under certain conditions, to be more fully described, an anode-cathode current can be caused to flow in a cold cathode resonant cavity magnetron. The magnitude of this current depends upon numerous factors, including the gas pressure within the tube, the anode voltage, and the amount of radio frequency power introduced within the cavity.

Further, there is a minimum value of radio frequency power necessary to maintain the anode current. This minimum, or threshold value, varies with the gas pressure within the tube.

The object of my invention is to utilize the above-described variation in current with pressure and radio frequency power to provide a method of measuring low gas pressures by means of a cold cathode resonant cavity magnetron.

In accordance with a preferred embodiment of my invention, I employ a cold cathode resonant cavity microwave magnetron. A low positive potential, of the order of 50 or 100 volts, is applied to the anode with respect to the cathode. An axial magnetic field, whose magnitude is close to the cyclotron value, as determined by the resonant frequency, is applied. Radio frequency power at the resonant frequency is supplied from an external source and introduced into the tube. As a result, a steady anode-cathode current flows.

For a more complete understanding of my invention, reference may be had to the accompanying drawings, in which Fig. 1 is a cross sectional view of a magnetron suitable for use in the invention; Fig. 2 is a schematic showing of the entire apparatus; Figs. 3, 4 and 5 are curves obtained as a result of experiments, Fig. 3 showing the variation of anode current with gas pressure, Fig. 4 showing the minimum R. F. power necessary to sustain the discharge at various pressures, and Fig. 5 showing the variation of anode current with applied R. F. power.

As shown in Fig. 1, the tube, designated generally by the numeral 10, is essentially a microwave magnetron. The anode block 11 has a number of identical slots 12 arranged symmetrically. The cathode 13 may be coated or uncoated. A conventional cathode heater (not shown) is provided but normally is not used. Radio frequency power is introduced into the

5 cavity between the cathode 13 and the anode 11 by means of a section of waveguide 14 which leads into the back of one of the slots 12. The transformer 15 and the window (not shown) are of conventional construction and may be, for example, of the type shown at page 497 of the book "Microwave Magnetrons" by Collins, McGraw-Hill, 1948.

10 It has been found that if a cold cathode magnetron such as above described be subjected to certain "critical conditions" that a current will flow between the anode and the cathode. These "critical conditions" are:

15 1. R. F. power, of the order of microwatts, the frequency of which is the resonant frequency of the tube, is incident on the tube.

2. An axial magnetic field, the magnitude of which is within a certain critical range in the neighborhood of the cyclotron field, is applied. (The cyclotron field is that value of field necessary to produce the well-known cyclotron oscillations in the usual magnetron.)

3. A positive voltage is applied to the anode with respect to the cathode.

25 Upon application of the critical conditions, the following effects may be observed:

1. After a period of time which may vary from a few seconds to a few minutes, an anode current, of the order of microamperes, starts to flow. The amount of time delay can be reduced by heating the cathode. Once the anode current begins to flow, the heater current may be turned off without interrupting the anode current. The amount of time delay depends on the previous history of the tube, being greater when the tube has been inactive for some time.

30 2. The anode current is a function of the gas pressure within the tube, as shown in Fig. 3.

3. The anode current flows only if the magnetic field is within a certain critical range in the neighborhood of the cyclotron field.

4. There is a lower limit to the anode voltage for which anode current will flow.

35 5. Anode current increases with an increase in R. F. power. There is a critical, or threshold, value of R. F. power, varying with pressure, below which the anode current will not flow. Fig. 4 is a curve showing this threshold power as a function of pressure.

40 The production of the anode current which flows upon application of the critical conditions is called the cyclotron effect. The following explanation is offered:

45 Consider an electron somewhere in the interaction space, subject to the critical conditions.

It will absorb power from the R. F. field and accelerate. The trajectory is such that before the electron reaches an electrode, it traverses a very long path, which is comparable in length to the mean free path of an electron in a gas at the pressure which exists in the tube. If the electron has acquired energy equal to or greater than the ionization potential of the residual gas, there is a likelihood that it will ionize a molecule. After the ionization, there are two free electrons available to start the process over again, and so the ionization increases. The electrons drift slowly toward the anode. The positive ions absorb power from the D. C. field and reach the cathode from which they liberate electrons. Depending upon the type of cathode surface, there may also be, at room temperature, some thermionic emission. The electrons at the cathode undergo a process similar to that described above for the initial electrons and so a steady anode current is obtained.

Fig. 2 shows the arrangement of the apparatus. A. D. C. potential is applied between anode 11 and cathode 13, the source being schematically shown as a battery 16 and a potentiometer 17. Anode current may be measured by a suitable instrument such as a microammeter 18. An axial magnetic field is provided by means of an electromagnet whose field coil 19 is supplied by a suitable adjustable source such as a battery 20 and a rheostat 21. R. F. power at the resonant frequency of the magnetron 10 is provided by a suitable source 22, such as a klystron oscillator. This R. F. power is fed to the resonant cavity of the magnetron 10. A calibrated R. F. attenuator 23 is inserted in the line between the source 22 and the magnetron 10. A switch 24 is provided so that the attenuator may be selectively inserted into or removed from the circuit. A wave meter 25 may be employed to measure the frequency of the power from the source 22. A monitor 26 to measure the power is provided.

In order to measure low gas pressures, the space 27, whose pressure is to be measured, is connected through a shut-off valve 28 to the interior of the magnetron 10. The connection may be made in any suitable manner. One manner which has been found to be satisfactory is to run a tubulation through the pole piece of the electromagnet. If desired, a pump 29 may be connected to the space 27 to maintain the low pressure. For the particular tube for which the curve of Fig. 3 was drawn, the R. F. power is at 8900 megacycles. Switch 24 is opened and the R. F. attenuator 23 is set so as to apply 150 microwatts to the tube 10. The critical magnetic field is about 3100 gauss. Anode voltage, which is not critical, is set to 50 volts. Microammeter 18 is read, and the pressure determined from the curve of Fig. 3. If desired, meter 18 can be calibrated to read pressure directly.

The above method is limited to measuring comparatively high pressures. One reason for the limitation is the inability of ordinary instruments to measure the low currents involved. A second method utilizes the fact that there is a minimum value of applied R. F. power necessary to maintain the anode current. This minimum, or threshold value, varies with pressure, as shown in Fig. 4. The apparatus is set up as above, except that the R. F. power is decreased by means of the attenuator 23 until the anode current is interrupted. The pressure is determined from the curve of Fig. 4. At extremely low pressures interruption of the anode current cannot be

observed with ordinary instruments. In order to note the minimum power necessary to sustain operation, use is made of the fact that once operation ceases, there is a time delay before it starts again. The R. F. power is, therefore, reduced in successive steps from some value at which anode current can be read conveniently, being returned to its initial value after each reduction. If anode current reappears immediately, it is an indication that the discharge has not been interrupted, while if it does not reappear immediately, the power has been dropped below the minimum necessary to sustain the discharge. The curve of Fig. 4 was plotted from experimental data. By means of the above technique and by extrapolation of the curve, pressures as low as 10^{-10} mm. of mercury have been determined.

It is sometimes desired to couple a source of R. F. power to a device whose R. F. impedance is adjustable. The apparatus used is that shown in Fig. 2. The tubulation leading to space 26 is closed by any suitable means, such as the valve 28. If desired, a sealed off magnetron may be used. The anode voltage and magnetic field are applied as before. Switch 24 is closed to remove attenuator 23 from the circuit. The impedance "seen" by the source 22 may be varied by adjusting the anode voltage.

In order to detect small amounts of R. F. power, the apparatus is set up as explained above. Valve 28 is closed, as before, or a sealed off tube is used. Switch 24 is closed to remove attenuator 23 from the circuit. The presence of an anode current indicates that R. F. power at the resonant frequency is incident upon the tube. Fig. 5 shows the relationship between anode current and R. F. power. Experimentally, an anode current has been sustained with an R. F. power as low as 10^{-11} watts.

It is to be understood that many variations in the structure and arrangement of parts may be made. For example, the particular anode structure shown in Fig. 1 is merely illustrative. Any other type of structure resonant at the same frequency may also be used. Similarly, the R. F. power may be introduced by any other suitable means, such as a coupling loop, instead of by means of the particular wave guide structure illustrated. The cathode may be coated or uncoated. At present, an uncoated cathode or seamless nickel tubing is preferred for measuring low pressure and for detecting small amounts of microwave power, while an oxide coated cathode is preferred for providing a variable impedance. The electromagnet may be replaced by a permanent magnet providing the same field strength. Many other modifications within the scope of my invention will suggest themselves to one skilled in the art.

The term "cold cathode" as used herein means a cathode which is not heated directly from an external source, as distinguished from the usual thermionic cathode which is heated by an external source provided for that purpose.

I claim:

1. The method of measuring low gas pressures by means of a cold cathode resonant cavity magnetron comprising the steps of connecting the interior of the magnetron to the space whose pressure is to be measured; applying to the magnetron an axial magnetic field whose magnitude is substantially that of the cyclotron field; applying a positive potential, below the cut-off value, to the anode with respect to the cathode; intro-

ducing sufficient radio frequency power at the resonant frequency into the cavity to initiate a measurable anode current; reducing the amount of radio frequency power successively in increasingly large steps; returning the power level to its original value after each reduction until the anode current fails to reappear immediately; whereby the least amount of power, which allows the anode current to reappear immediately when the power level is restored, is a measure of the 10 pressure within the space.

2. In a method of measuring low gaseous pressures by means of a cold cathode resonant cavity magnetron, the steps of connecting the space whose pressure is to be measured to the interior of said cold cathode resonant cavity magnetron, applying an axial magnetic field the magnitude of which is within a certain critical range in the neighborhood of the cyclotron field; applying a positive potential below the cut-off value to the anode of the magnetron with respect to its cathode; introducing radio frequency power at the resonant frequency into the magnetron, whereby a steady anode-cathode current flows; and reducing the amount of radio frequency power until the minimum value of said radio frequency power necessary to maintain the anode-cathode current at its threshold value is determined, the amount of power introduced at the instant the anode-cathode current is at said threshold value being a measure of the pressure within said space.

3. A method for measuring low gaseous pressures by means of an apparatus which comprises a cold cathode resonant cavity magnetron, said magnetron having an axial magnetic field incident thereon whose magnitude is substantially equal to the cyclotron field value, said magnetron also having a positive potential below the cut-off value applied to the anode, said method comprising the steps of connecting the space whose pressure is to be measured to the interior of said cold cathode resonant cavity magnetron, intro-

ducing sufficient radio frequency power into the cavity of the magnetron to cause a steady anode current to flow, and reducing the amount of radio frequency power until the minimum value of said radio frequency power necessary to maintain the anode current at its threshold value is determined, the amount of power introduced at the instant the anode current is at said threshold value being a measure of the pressure within said space.

4. A method for measuring low gaseous pressure by means of a resonant cavity cold cathode magnetron operating with an anode voltage below cut-off and a magnetic field substantially equal to the cyclotron field value, the interior of the magnetron communicating with the space whose pressure is to be measured, comprising the steps of applying sufficient radio frequency power, at the resonant frequency, to the magnetron to cause a measurable steady anode current to flow; reducing the amount of radio frequency power and immediately returning the power to its original value; successively repeating the foregoing step with increasing reductions in the amount of power until the anode current fails to reappear immediately, whereby the least amount of power which sustains the anode current is a measure of the pressure within the space.
